CLAIM

The ornamental design for a waste scoop, as shown and described.

DESCRIPTION

FIG. 1 is a top front perspective view of a waste scoop, showing my new design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof;

FIG. 6 is a bottom plan view thereof; and,

FIG. 7 is a top front perspective view of the waste scoop shown in a used condition.

The equally sized broken lines showing a shaft of the waste scoop in FIG. 7 depicts environmental subject matter that forms no part of the claimed design, while the remaining equally sized broken lines shown in the drawings depict portions of the waste scoop that form no part of the claimed design.

The alternating sized broken lines depict the bounds of the waste scoop that form no part of the claimed design.
